UNITED STATES PATENT OFFICE

2,005,927

BRAKE BEAM FULCRUM

Walter H. Baselt, Chicago, Ill., assignor to American Steel Foundries, Chicago, Ill., a corporation of New Jersey

Application March 17, 1933, Serial No. 661,220

13 Claims. (Cl. 188—231)

This invention relates to improvements in brake beam fulcrum, including a compression member seat, a tension rod seat and a support for a third point support casting.

5 It is an object of the present invention to disclose an improved design of brake beam fulcrum with an enclosed rod seat adapted to be associated with a third point support casting whereby a limited pivotal movement of the third point support casting is provided, at the same time maintaining the desired strength of the 10 brake beam fulcrum.

15 It is a specific object of the present invention to disclose a brake beam fulcrum having an enclosed rod seat to prevent displacement of the tension rod and in which the rod seat is partially cut away to permit pivotal movement of the third point support casting.

20 With these and various other objects in view, the invention may consist of certain novel features of construction and operation as will be more fully described and particularly pointed out in the specification, drawing and claims appended hereto.

25 In the drawing:

Figure 1 is a plan view of the brake beam fulcrum shown in partial section;

Figure 2 is a side elevation of the brake beam fulcrum and associated support casting;

30 Figure 3 is a detail section on line 3—3 of Figure 1;

Figure 4 is a fragmentary plan view partially in section showing a modified construction of the brake beam fulcrum;

35 Figure 5 is a detail section taken on line 5—5 of Figure 4, and

Figure 6 is a side elevation of Figure 4.

Referring first to the construction shown in Figures 1, 2 and 3, inclusive, the brake beam ful-

40 crum 10 is a one piece casting having pivots 12 intermediate its ends for supporting a brake lever and a support for a brake beam compression member 14 at one end. The other end has an enclosed seat 16 to receive the tension rod.

45 The side walls 18 extend beyond the rod seat 16 and are provided with openings 20 adapted to receive pin 22 for pivotally supporting the third point support casting 24. The distance from the rod seat 16 to the center of the openings

50 20, which provide pivotal support for the third point support casting, is limited and it is therefore necessary to provide the required strength in the limited space and at the same time arrange for swivelling movement of the third point support casting. As shown in Figure 3 the up-

per wall 26 of the rod seat between the side walls 18 is elongated and formed parallel with the slightly elongated bottom wall 28. Extension of the upper wall 26 of the rod seat, as shown in Figure 3, considerably reinforces the lug or side walls 18. The rod opening is elongated in the direction of the longitudinal axis of the fulcrum to provide clearance for the insertion and assembling of the rod and enlarged or curved outward from its mid-point to form the rod seat 16. In this construction due to the extension of the wall or web member 26 beyond the bottom wall or web 28, the third point support is allowed greater pivotal movement in its normal position than it would have in an inverted position.

5 In the modified constructions of Figures 4, 5 and 6 the brake beam fulcrum 30 is formed with an enclosed rod seat 32 and a pair of lugs 34 having openings 36 for the pivotal support of the third point support casting. Between the lugs 34 the top wall 38 and the bottom wall 40 are curved towards each other but their ends are spaced from each other to leave a cut-out to permit free swivelling movement of the third point support 15 casting. The walls 38 and 40 however serve to reinforce the lugs 34.

20 It is to be understood that, in both forms of the brake beam fulcrum disclosed, an enclosed tension rod seat is provided to prevent displacement 30 of the rod upon breakage thereof and that this arrangement is provided together with a pivotal support for a third point support casting, the brake beam fulcrum being so designed that free swivelling movement of the third point support 35 casting may occur while the lugs which support the third point casting are reinforced by the upper and lower walls of the rod seat.

25 It is to be understood that I do not wish to be limited by the exact embodiment of the device 40 shown, which is merely by way of illustration and not limitation, as various other forms of the device will of course be apparent to those skilled in the art without departing from the spirit of the 45 invention as ascertained from the scope of the appended claims.

I claim:

1. In combination, a brake beam fulcrum having an aperture forming a pivotal seat for a third 50 point support, a third point support secured to said seat, said fulcrum having an aperture therein adjacent said first-mentioned aperture forming a substantially enclosed rod seat, a portion of the wall of said rod seat being omitted to pro- 55

- vide clearance for pivotal movement of said third point support.
2. In combination, a one piece brake beam fulcrum having an aperture forming a pivotal seat 5 for a third point support casting, a third point support casting pivotally carried by said seat, said fulcrum having an aperture therein adjacent said first mentioned aperture forming a substantially enclosed tension member seat, a portion 10 of the wall of said tension member seat being omitted to provide clearance for pivotal movement of said third point support.
3. In combination, a brake beam fulcrum provided at one end with aligned openings, a third point support pivoted in said aligned openings, 15 a substantially enclosed tension member seat formed in said fulcrum adjacent said aligned openings, the wall of said enclosed seat being omitted to provide clearance for pivotal movement of said third point support.
4. In combination, a brake beam fulcrum provided at one end with aligned openings, a third point support pivoted in said aligned opening, a substantially enclosed tension member seat 20 formed in said fulcrum adjacent said aligned openings, the wall of said enclosed seat being omitted to provide clearance for pivotal movement of said third point support, said enclosed seat being tapered from its mid-point toward the 25 outer ends thereof.
5. In combination, a brake beam fulcrum having a substantially enclosed tension member seat, lugs extending from the opposite ends of said seat, said lugs being provided with aligned openings, a third point support journalled in said 30 aligned openings, the enclosing wall of said seat being partially omitted to provide clearance for limited pivotal movement of said third point support.
6. A brake beam fulcrum having an enclosed tension member seat, said fulcrum being provided with extensions at the opposite ends of said seat, said extensions having aligned openings, a third point support journalled in said openings, 35 said extensions being aligned with said tension member seat longitudinally of said fulcrum, said seat having reinforcing top and bottom webs between said extensions.
7. In combination, a brake beam fulcrum having a substantially enclosed tension member seat, said fulcrum being provided with extensions at the opposite ends of said seat, said extensions having aligned openings and a third point support pivoted in said aligned openings, said seat 40 having reinforcing top and bottom web members between said extensions, said web members serving to limit the pivotal movement of said third point support.
8. A brake beam fulcrum having a substantially enclosed rod seat elongated in the direction of the longitudinal axis of said fulcrum, said fulcrum being provided with extensions at the opposite ends of said rod seat, said extensions having aligned openings, a third point support journalled in said openings, said extensions being aligned with said rod seat longitudinally of said fulcrum, said rod seat having top and bottom web members between said extensions. 5
9. In a brake beam fulcrum having a substantially enclosed rod seat, said fulcrum being provided with extensions at the opposite ends of said rod seat, said extensions having aligned openings, a third point support journalled in 10 said openings, and said rod seat being partially omitted between said extensions. 15
10. In combination, a brake beam fulcrum having a rod seat enclosed at its opposite ends, said fulcrum including extensions from the enclosed ends of said seat, a third point support journalled in said extensions, said rod seat including top and bottom walls intermediate said extensions constituting reinforcements thereof and permitting limited pivotal movement of said 20 third point support.
11. A brake beam fulcrum having a substantially enclosed tension member seat, said fulcrum being provided with extensions at the opposite end of said seat, said extensions having aligned 25 openings, a third point support journalled in said openings, said seat having reinforcing top and bottom webs between said extensions, one of said webs extending beyond the other of said webs towards the end of said fulcrum. 30
12. A brake beam fulcrum having a substantially enclosed tension member seat, said fulcrum being provided with extensions at the opposite end of said seat, said extensions having aligned 35 openings, a third point support journalled in said openings, reinforcing web members between said extensions serving to limit the pivotal movement of the third point support, one of said webs extending closer to the end of the fulcrum than the other of said webs. 40
13. In combination, a brake beam fulcrum having a substantially enclosed tension member seat, said fulcrum being provided with extensions at the opposite ends of said seat, said extensions having aligned openings and a third point support pivoted in said aligned openings and means formed integral with said fulcrum comprising top and bottom web members extending from said seat between said extensions, one of said web members extending closer to the end of said 45 fulcrum than the other of said web members. 50
